Primary Examiner — Cynthia R Underwood*(74) Attorney, Agent, or Firm* — VIA LLP(57) **CLAIM**

The ornamental design for a carabiner, as shown and described.

DESCRIPTION

FIG. 1 is a perspective view showing front, right and top surfaces of a carabiner, embodying my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The dash-dash broken lines in the drawings illustrate portions of the carabiner which form no part of the claimed design. The dash-dot broken lines are boundaries of the claimed design, which boundaries form no part of the claimed design.

1 Claim, 5 Drawing Sheets(56)
